UNITED STATES PATENT OFFICE.

RAY O. HARDING, OF ROCKFORD, ILLINOIS, ASSIGNOR OF ONE-HALF TO JOSEPH P. CORLEY, OF ROCKFORD, ILLINOIS.

MENU-CARD HOLDER.

Application filed November 22, 1926 Serial No. 149,860.

This invention relates to loose leaf holders generally but more particularly to holders for menu cards and the like.

The principal object of the invention is to provide a much simpler and cheaper construction in a menu card holder which, furthermore, has the advantage that the card is more securely held and does not have to be buckled or wrinkled and possibly soiled and torn when being inserted in the holder.

According to the present invention, a plurality of small elongated eyelets are provided on a single strip fastened in the back of the holder, the eyelets being arranged for engagement through apertures provided therefor in the crease of the folded card to be inserted in the holder, and a wire pin of about the length of the back is provided to be entered through the eyelets over the leaf to retain the same in place. An additional feature of advantage in this construction, aside from its direct appeal in view of its simplicity, is the fact that the pin is held in place in the eyelets solely by reason of the close friction fit therein so that no additional means which would make the construction complicated and expensive to manufacture is required. A still further feature of distinct advantage from the practical standpoint lies in the construction of the back of flexible material, such as leather, in which any rough or sharp edges of the metallic parts used in the building up of the back of the holder are properly covered and concealed so that the holder presents a more pleasing appearance, is nicer to handle and there are no sharp or rough parts to cut or abrade the hands or possibly mar the surface of the table or counter where the holder is used.

These and other features of the invention will be brought out in the course of the following detailed description having reference to the accompanying drawing, wherein—

Figure 1 is a face view of a menu card holder opened out, the same being shown without a card inserted therein so as better to show the construction;

Fig. 2 is a somewhat enlarged longitudinal section through the back of the holder with a menu card inserted therein;

Fig. 3 is a fragmentary view of the middle of a menu card showing the apertures at the crease; and

Fig. 4 is a transverse section through the

back of the holder to show the use of several plies of flexible material in the construction of the back and to further illustrate the way in which the menu card is held in place. The same reference numerals are applied to corresponding parts in the four views.

The holder comprises a back 5 of flexible material, preferably leather, having a pair of cover members 6 attached thereto, the latter being made in any way desired and each may be suitably provided with advertising matter beneath covering of transparent celluloid and bound together at the edges by a strip 7 to give the desired body and also make for permanence. The back has a metal strip 8 secured thereto as by means of rivets 9. The strip is preferably of thin sheet metal folded to double thickness, as shown in Fig. 4, for rigidity and has a plurality of small elongated eyelets 10 provided by rolled struck up portions at intervals the length of the strip. The eyelets are arranged to be received in elongated apertures 11 provided at the crease in a menu card 12. A pin 13, suitably of wire of rather small gauge, is arranged to be threaded through the eyelets 10 over the card 12 to retain the same in place in the manner indicated in Fig. 2. A flat, round head 14 is provided on the end of the pin 13 to facilitate pushing the pin through the eyelets or pulling the same therefrom. The head 14, if desired, may be left at about the position shown in Fig. 1 so as not to obstruct the closing of the folder, although the position thereof is relatively unimportant. The elongation of the eyelets, combined with the close fit with which the pin is received therein provides ample friction to retain the pin against dropping out or working loose. The eyelets are approximately in alignment although the absolute alignment thereof is not required since the pin 13, being of small gauge wire, can be thrust to one side or the other due to its flexibility and conformability and can thus be threaded through the series of eyelets without difficulty. In fact, any slight lack of alignment between the eyelets will only serve to increase the friction with which the pin 13 will be held in place. The novel manner of holding a menu card as herein described avoids the necessity for buckling or wrinkling the card when inserting the same in the holder. There is absolutely no danger of soiling or possibly tearing the card as there was in the

case of holders of other designs with which I am familiar, as the card is inserted opened out flat.

The back 5, being of leather, affords sufficient flexibility in the connection between the covers 6 so that the complicated and expensive hinge connections otherwise employed are rendered unnecessary. Furthermore, the leather back makes the holder much nicer to handle as there is no possibility of cutting or abrading the hands as there was in the case of the holders having a back of metallic construction with hinges for mounting the covers; as in these cases there was always apt to be some part presenting sharp or rough edges. The leather backed holder is also preferable from this practical consideration that it eliminates any danger of marring the surface of the table or counter on which the holder may be placed. The back 5 is preferably made of one-piece of leather with the two ends skewed off and lapped together at 15 inside the holder. The edges are sewed to the covers, as indicated at 16, and the two plies are also sewed together across the ends, as indicated at 17. The strip 8 is riveted to the ply just beneath it, as indicated in Fig. 2, and has its opposite ends entered through slits 18 in this ply so as to cover up the rough edges which would otherwise be presented at the ends of the strip. The ends of the rivets 9 are thus concealed by the outer ply of leather on the back of the holder, while the ends of the strips are covered by the inner ply within the holder. There is thus no danger at all of any part of the metallic strip 8 giving trouble and the same is true of the rivets 9. In the handling of the holder and when the same is laid on the table or counter, nothing but protected surfaces can come in contact with the hands or the surface of the table or counter. The strip 8, besides providing a mounting for the eyelets 10, also serves as a stiffener for the material of the back 5 which might otherwise tend to be so limp as to prevent the covers from closing properly one onto the other with their edges together.

The foregoing description is believed to make clear the novel manner of operation of the holder of the present invention as well as to bring out the advantages from the standpoint of service and cost which the same presents over previous types of loose leaf holders of this character.

55 I claim:

1. A loose leaf holder of the character described comprising a back of flexible material having a pair of cover members attached to the longitudinal edges thereof, a narrow flat strip of rigid material extending lengthwise of the back midway between the covers and attached thereto, said strip serving to

stiffen the otherwise limp material of the back as well as lend definite form thereto so that the covers will fold properly onto one another, eyelets provided on said strip and arranged for engagement through apertures in a leaf to be inserted in the holder, and a pin approximately the length of the back passed through the eyelets over the leaf to retain the latter in place. 65 70

2. A structure as set forth in claim 1, wherein the eyelets are elongated to tubular shape and the retaining pin is of a small gauge wire and hence much more flexible and 75 conformable than the back strip to enable threading the same through the plurality of elongated eyelets without regard to the matter of whether the eyelets are absolutely in alignment, any slight lack of alignment serving only to increase the frictional hold of the eyelets on the pin. 80

3. A loose leaf holder of the character described, comprising a back of flexible material having a pair of cover members attached thereto, a sheet metal strip extending lengthwise of the middle of the back and attached thereto, said strip serving to reinforce and give body to the otherwise limp material of the back so that the covers will fold properly 85 one onto the other, eyelets provided by struck up portions of said strip and arranged for engagement through apertures in the crease of a folded leaf to be inserted in the holder, and a pin of approximately the length of 90 the back passed through said eyelets over said leaf to retain the latter in place, said pin being retained in said eyelets solely by its friction fit therein. 95

4. A loose leaf holder of the character described comprising a back formed from a single strip of flexible material folded to give a double thickness, namely an inside ply and an outside ply, a pair of cover members attached to the back by marginal edges entering between the plies of the back, a narrow flat strip of rigid material extending lengthwise of the middle of the back between the covers having the ends thereof passed through slits in the inner ply so that the raw ends are concealed between the two plies of the material of the back, said strip being attached to the back and serving to reinforce and give body and definite form to its otherwise limp material so that the covers will fold properly onto each other, eyelets provided on said strip and arranged for engagement through apertures in a leaf to be inserted in the holder, and a pin passing through the eyelets over said leaf to retain the latter in place. 100 105 110 115 120

In witness of the foregoing I affix my signature.

RAY O. HARDING.
